UNITED STATES PATENT OFFICE.

THOMAS J. WOODROW, OF FOUNTAIN PARK, OHIO.

NECK-YOKE.

No. 823,574.

Specification of Letters Patent.

Patented June 19, 1906.

Application filed November 8, 1905. Serial No. 285,753.

To all whom it may concern:

Be it known that I, THOMAS J. WOODROW, a citizen of the United States, residing at Fountain Park, in the county of Champaign and State of Ohio, have invented certain new and useful Improvements in Neck-Yokes, of which the following is a specification, reference being had therein to the accompanying drawings.

10 This invention relates to an improvement in neck-yokes, and more particularly to the pole-support or hanger of the neck-yoke; and the object of the invention is the provision of a hanger of this character by means of which the pole and neck-yoke may be locked together when in use, but may be readily disconnected when desired.

Other objects of the invention will be apparent from the detailed description herein-
20 after when read in connection with the accompanying drawings, forming part hereof, wherein a preferable embodiment of my invention is shown and wherein like numerals of reference refer to similar parts in the drawings.

25 In the drawings, Figure 1 is a front elevation of a neck-yoke provided with my improved hanger, and Fig. 2 is a vertical section on line 1 1 of Fig. 1 with the pole secured in position within the hanger.

Referring now more particularly to the drawings, A designates the pole-hanger, which is in the form of a U-shaped loop of a substantially flat formation and the inner 35 portion of which is provided with an inwardly-extending recess a, in which the usual crescent-shaped flange b of the pole B is designed to fit when the pole is secured in position within the hanger. The upper extre-
40 mities of the arms of the U-shaped hanger A are provided with the enlarged ears a', in which is rigidly secured the cross-bar a''. The inner edge of one of the arms of the U-shaped hanger A is provided adjacent its upper end with an outwardly-extending lip a'', which affords an entrance to the recess a. C designates a clip which is rigidly secured in any suitable manner to the intermediate portion of a neck-yoke D and which is provided with
45

50 a downwardly-extending portion which loosely embraces the cross-bar a'' intermediate the arm of the U-shaped hanger A. The under side of the portion of the clip C, which embraces the cross-bar a'', is made somewhat thinner than the side portions thereof, as is shown in Fig. 2, for a purpose to be herein-
55

after more particularly set forth. The distance between the lower edge of the portion of the clip C which embraces the cross-bar of the U-shaped hanger and the lower portion 60 of said hanger is slightly less than the combined height of the pole B and the crescent-shaped flange b secured thereon.

To secure the neck-yoke in position upon the pole, the U-shaped hanger A is slipped 65 upon the pole with the neck-yoke D depending therefrom and with the side which is provided with the lip a' facing the crescent-shaped flange b on the pole B. The neck-yoke is then turned so that the clip C secured there-
70 to extends substantially at right angles to the U-shaped hanger, and the hanger is pressed rearwardly along the pole until the flange b secured thereon contacts with the thin portion of the part of the clip C which 75 embraces the cross-bar a''. With the parts in this position the U-shaped hanger A is turned about the pole until the neck-yoke is brought to the upper side thereof. During the turning of the hanger A upon the pole the 80 lip a' thereof will engage the flange b on the pole B and guide the same into the inwardly-extending recess a in the hanger. Accidental disengagement of the pole from the hanger is prevented by the fact that the side of the 85 downwardly-extending portion of the clip C which embraces the cross-bar of the hanger is made thick enough to project beyond the lip a' of the hanger when the parts are in their normal position. To disengage the 90 neck-yoke from the pole, it is first necessary to move the same so that the clip C secured thereto extends substantially at right angles to the hanger A. The hanger A is then rotated until the neck-yoke is brought to a position below the pole, which will cause the flange of the pole to emerge from the recess a in the hanger A through the lip a' and onto the thin portion of the clip C surrounding the cross-bar a''. The neck-yoke can then be 95 slipped off the end of the pole.

I do not desire to limit myself to the precise form and construction shown in the drawings, as it is obvious that many minor changes might be made thereto without departing from the spirit of the invention.

What I claim as my invention, and desire to secure by Letters Patent, is—

1. The combination with a neck-yoke, of a pole-hanger provided with a recess to accommodate the holdback-flange of the pole, and a clip connecting said hanger with the neck-

yoke, said clip having a projection extending normally beyond the plane of said recess.

2. The combination with a neck-yoke, of a substantially **U**-shaped pole-hanger provided on its interior with an inwardly-extending recess to accommodate the holdback-flange of the pole and one of the arms of said hanger having an outwardly-extending lip affording an entrance to said recess, and means pivotally connecting said hanger to the neck-yoke.

3. The combination with a neck-yoke, of a substantially **U**-shaped hanger provided on its interior with an inwardly-extending recess to accommodate the holdback-flange of the pole, one of the arms of said hanger having an outwardly-extending lip affording an entrance to said recess, and a clip pivotally connecting the upper end of said hanger with the neck-yoke, said clip being provided with a portion normally projecting beyond the plane of the entrance to said recess.

4. The combination with a neck-yoke, of a substantially **U**-shaped hanger provided on its interior with an inwardly-extending recess to accommodate the holdback-flange of the pole, one of the arms of said hanger being provided with means affording an entrance

to said recess, a cross-bar rigidly connecting the upper ends of the arms of said hanger, a clip secured to the neck-yoke and loosely embracing the cross-bar of the hanger, a portion of said clip extending normally beyond the plane of the entrance to said recess.

5. The combination with a neck-yoke, of a substantially **U**-shaped pole-hanger secured thereto and provided on its interior with an inwardly-extending recess to accommodate the holdback-flange of the pole, said hanger having an outwardly-extending lip affording an entrance to said recess.

6. The combination with a neck-yoke, of a substantially **U**-shaped hanger provided on its interior with an inwardly-extending recess to accommodate the holdback-flange of the pole, and a clip pivotally connecting the upper end of said hanger with the neck-yoke, said clip being provided with a portion normally projecting beyond the plane of the entrance to said recess.

50
In testimony whereof I affix my signature in presence of two witnesses.

THOMAS J. WOODROW.
